UNITED STATES PATENT OFFICE.

RAYMOND F. BACON, OF NEW YORK, CLEO H. KIDWELL, OF NEW BRIGHTON, NEW YORK, AND PERRY H. BASCOM, OF BOUND BROOK, NEW JERSEY, ASSIGNEES, BY MESNE ASSIGNMENTS, TO VAN HEUSEN PRODUCTS, INC., A CORPORATION OF DELAWARE.

FABRIC-TREATING MACHINE.

Application filed July 19, 1922. Serial No. 575,958.

To all whom it may concern:

Be it known that we, RAYMOND F. BACON, of New York city, county and State of New York, CLEO H. KIDWELL, of New Brighton, 5 Richmond County, New York, and PERRY H. BASCOM, of Boundbrook, Somerset County, State of New Jersey, all citizens of the United States, have invented certain new and useful Improvements in Fabric-Treating Machines, of which the following is a 10 description.

This invention relates to improvements in fabric treating machines and more particularly to machines adapted to treat fabric 15 or certain portions thereof with fluids.

In the copending applications of Raymond F. Bacon and Cleo H. Kidwell, Serial Nos. 544,320 and 548,604, filed March 16, 1922 and April 1, 1922, respectively, the 20 treatment of fabric with a solution of sulphuric acid is described. As set forth in these applications, the method by which the material is treated depends in part on the thickness and weight of the fabric and also 25 on the tightness of the weave. For example, a heavy fabric such as multiple ply interwoven fabric made up of a plurality of layers of fabric bound integrally together by binder or interweave threads, requires 30 some positive means of forcing the acid into and through the fabric. On the other hand, a light flimsy fabric as, for example, handkerchief cloth, does not require the acid to be forced or drawn through but may, for 35 its treatment, simply be dipped in the desired solution.

The present invention relates to a machine adapted to treat woven fabrics of any weight or weave, and particularly heavy 40 tightly woven fabrics, it being provided with means for forcing or drawing the solution through the fabric. According to the preferred embodiment of the invention we do not treat the entire fabric but only certain 45 portions thereof, the said treated portions being spaced at any desired distance along the strip of fabric.

We will now describe roughly the construction and operation of the machine of our invention, the details of which we will 50 discuss hereinafter in connection with the drawings. The machine proper consists of a suitably supported metal top or table provided with two sets of rollers, one set at each end of the table. The fabric to be 55 treated passes through the first set of rollers, which are not actuated but simply guide the fabric and maintain a slight tension thereon, and, after the treatment, through the second set of rollers which are actuated 60 and draw the fabric through. The treated fabric is then picked up by a series of prongs or projections on a conveyor belt and transferred to a series of baths in which the acid or other solution is washed 65 out. The fabric then passes out of the baths and through a series of hot rollers which press the moisture out of the fabric and then dry it, thus completing the treatment.

Supported on the table of the machine 70 are two large members between which the fabric passes, one member being directly above the other. We shall hereafter refer to the upper member as the platen and the lower member as the bed plate. The bed 75 plate is set into the upper surface of the table and is stationary, while the platen is set between two vertical guide rails and is free to move up or down. This movement of the platen is occasioned by two cams on 80 which rest two corresponding arms projecting down from the platen. While we have referred to the upper member or platen as being the reciprocating member, it is, of course, obvious that either or both of the 85 upper and lower members may be reciprocating, the important thing being that the two members are relatively movable.

The platen is constructed in the form of a hollow shell. That is, it is made so that 90 the chemical solution with which the fabric is to be treated can be contained therein. The lower face of the platen is made of a hard porous material which will, under or,

inary atmospheric pressure conditions, hold the solution without permitting any leakage there through. This material, however, will allow the solution to pass through when pressure is applied to the upper surface of the solution, or when suction is applied to the lower face of the porous material, and is therefore pervious to that extent. The upper surface of the bed plate is also constructed of pervious material, and the pervious portions of both the platen and bed plate are of the same size and shape so that when the platen is brought down over the bed plate, the pervious portion of the former covers the pervious portion of the latter. Under the table and connected to the bed plate is an air tight chamber with a drain pipe and valve through which any accumulation of the chemical solution may be drawn off, and also an air pipe connected to a vacuum pump which continuously pumps air out of the chamber.

In the operation of the machine, the fabric is drawn by the rollers above mentioned between the platen and bed plate while the platen is raised. When the desired length of fabric has been pulled through the driven roller stops, thus leaving the fabric suspended between the rollers at each end of the machine and at the center of the machine lying as aforesaid in a flat strip between the platen and bed plate. The platen then moves down and presses the fabric firmly between its lower face and the upper face of the bed plate. Immediately a suction is produced by the evacuated chamber under the bed plate and the solution passes through the pervious material of the platen, through the fabric which is pressed between the members, through the pervious material of the lower jaw, and into the chamber. The fabric is thus completely saturated with the solution at that portion thereof which lies between the pervious faces of the bed plate and platen. It will be obvious that the entire lower face of the platen and the entire upper face of the bed plate may be made of pervious material or only those portions thereof desired, depending on whether all or only a certain part of the fabric between the members is to be treated.

When enough solution has been drawn through the fabric to treat it thoroughly, the platen moves upward, thus breaking off the suction of the bed plate and chamber and stopping the flow of acid. Also the fabric is now released from its position between the members and the driven roller begins to operate and draws the fabric through to the next portion which it is desired to treat. The operation is then repeated for each successive treatment of the fabric.

Our invention will be further described in connection with the accompanying draw-

ings illustrative of one embodiment thereof, in which—

Fig. 1 is a side elevation showing diagrammatically the entire apparatus,

Fig. 2 is a sectional elevation taken along the line 2—2 of Fig. 1,

Fig. 3 is a sectional view taken on the line 3—3 of Fig. 2,

Fig. 4 is a plan view of the machine,

Fig. 5 is a sectional view taken on the line 5—5 of Fig. 3,

Fig. 6 is a sectional view taken on the line 6—6 of Fig. 3, and

Fig. 7 is a plan view of the bed plate.

In the drawings we have illustrated a machine adapted for use in the manufacture of collars, and more particularly of collars made of multiple ply interwoven fabric. As described in the copending application of Raymond F. Bacon and Cleo H. Kidwell, Serial No. 548,604, filed April 1, 1922, the multiple ply interwoven fabric is treated with sulphuric acid along a narrow strip or zone following the outline of the collar. After the treatment has been completed the collar is cut out along the treated zone and the cut edges of the collar are, in effect, selvaged. That is, the cut edges will not ravel or fray and the necessity for a binding on the cut edges is obviated.

It will be understood that we do not intend to limit ourselves to the machine illustrated or to the detailed description herein-after set forth, but that many variations may be made in the construction thereof depending, for example, on the shape or size of the portion it is desired to treat, and on the nature and type of chemical solution which is used.

Similar numerals refer to similar parts throughout the several views.

The entire apparatus of the preferred embodiment of our invention is diagrammatically illustrated in Fig. 1. In the figure, the fabric 1 enters the tension rolls 2, passes between the platen 3 and the bed plate 4 which are shown in their separated position, and out through the driven rolls 5. It will be noted that the rolls 5 are provided with roughened surfaces such as a series of sharp projections to insure a firm and positive grip on the fabric. After passing through the rolls 5 the fabric is caught in a series of loops by the prongs or projections 6 extending from the conveyer belt 7. The conveyer belt is driven by the chain 8 from the sprocket 9, the operation of which will be hereinafter fully described. The speed of the said conveyer belt is timed so that exactly one minute elapses from the time the fabric leaves the rolls 5 until it is deposited in the bath 10. The rolls 11 which pass the fabric from the conveyer to the bath may be actuated in any desired manner. These must, of course, be timed to take up the fabric at

the proper speed. The baths 10 and 11' as shown in Fig. 1 are connected by the pipe 12, a continuous current of water or of an alkaline solution passing from inlet pipe 13 through bath 11', through pipe 12 into bath 10 and into outlet pipe 14. It may be found desirable to separate baths 10 and 11' and to use running water in bath 10 and an alkaline solution, for example ammonium hydroxide, in bath 11'. Rolls 15 and 16 may be driven from the same source as rolls 11. Rolls 17 are heated and the fabric dries on passing through them. Any other suitable drying means may be employed if desired. It may be found desirable to heat also rolls 16 in order to insure the thorough drying of the treated fabric.

The drain 18 is lead lined and is intended to catch any acid that may drip from the fabric as it is passing to the baths.

As before stated, the platen is so constructed that it may be raised or lowered. The arms 19 (Fig. 2) are cast integral with or, if desired, bolted to the metal frame 20 of the platen and are provided with ears 21 which slide on the guide rails 22. The two arms 19, which extend downward from the platen, rest on the cams 23. These cams are fastened to shaft 24 which is driven by the motor 25 shown in Fig. 4. The shaft 24 turns in the bearings 26 which are supported by L beams 27, said L beams running the length of the machine and being bolted to the legs 28. The guide rails 22 are secured with bolts 29 to ears 30 extending from the metal cross piece 31 (Fig. 5). In Fig. 6 the ears 21 which are attached to the arm 19 are shown running on the guide rail 22. The cam 23 sliding on the bottom face of arm 19 is attached to shaft 24.

The platen 3 has a removable inner portion 33 (Fig. 2) in which is contained the acid solution 34. This removable portion is made up of a pervious portion 35 and a portion 36 of cast lead or other suitable impervious material. The pervious portion is made up of a hard porous substance which is not affected by sulphuric acid and which has a sufficient degree of porosity to allow the acid to flow through it when suction is applied to its under surface, and which will retain the acid without leakage when the suction is removed. Materials such as white sand (silica) mixed with a suitable binder, for example, kaolin, and baked in the desired shape will give good results. We have found, however, that "alundum" (aluminum oxide with a silicate binder) gives the best results and we prefer to use it rather than white sand. The degree of porosity of the alundum may vary, depending on the solution used and also on the amount of suction available. We prefer to use alundum which will allow sulphuric acid (75% by weight) to pass through freely under a difference

in pressure of about 45 to 50 cms. of mercury. The narrow portions 37 are those through which the acid flows when suction is applied. The remaining portion of the lower surface of the pervious material or 70 ceramic is covered by the plate 38 which acts both as a covering to prevent acid from passing through and also as a supporting member. The narrow portion 37 follows the outline of a collar as illustrated in Fig. 75 7, so that when the acid is drawn through the fabric the treatment will be limited to the narrow zone 37 describing the outline or contour of a collar.

In making the removable portion we have 80 found it advisable first to make the pervious ceramic, and, when it is completed, to pour molten lead around it in a form so that the side walls 36 of the removable portion are lead and also so that the lead will flow in 85 around the irregular shaped ceramic and make a tight joint at the portions 39. The removable portion is held in place by the plates 40 attached to the platen frame, or by any other suitable means which may if 90 desired overlie the entire fluid container and serve as a cover for it. It will be obvious that for different sizes and styles of collars ceramics having effective pervious outline 95 of different shapes and sizes will be necessary and for this reason it is necessary to have a series of removable and interchangeable portions 33. The outside dimensions of the removable portions 33 will remain constant, the outline or shape of the narrow 100 zone 37 being the only variable.

Directly below the zone 37 of the upper jaw is the bed plate zone of identical width and shape, and also made of similar pervious material. The lead portion 40 of the bed 105 plate is cast around the pervious portion 41 of the bed plate in the same manner as above described in connection with the platen. So also the bed plate is removable, it being secured to the table by bolts 42 110 placed through holes 42'. Whenever the removable portion of the platen is changed a corresponding change must be made in the bed plate.

Under the bed plate is a vacuum chamber 115 43. The upper walls of this chamber are formed by the lead portion of the bed plate. The sides and bottom of the cavity are the lead lined inner surface of the casting 31. In the cast lead portion 40 of the bed plate 120 and directly under the pervious zones 37 a large number of very small holes are drilled. These drilled lead portions are indicated at 44 in Fig. 2 and they extend from the pervious material at the top to the chamber 125 43 at the bottom. The drain pipe 45 is connected with a closed tank into which flows the acid that is drawn into the chamber 43. The tank is provided with a suitable valve 130 so that the acid may be drawn or pumped

off. The pipe 46 shown in Fig. 1 extends into the chamber 43. This pipe is connected to a tank or container 47 (see Fig. 1) filled with activated charcoal which will remove any acid fumes from air passing therethrough. Another pipe connects the charcoal tank with a vacuum tank 48 to which the vacuum pump 49 is connected.

The vacuum pump 49 is operated continuously so that, when the platen and bed plate are apart, a steady current of air is drawn through the previous material of the bed plate at the zone 37, through the drilled lead 44, into the partially evacuated chamber 43, down the air pipe 46, through the container 47 into the vacuum tank 48 and out through the pump 49. When the platen is down on the bed plate with the fabric pressed therebetween the air inlet is cut off and the suction is exerted on the acid 34 in the platen. The acid is drawn through the zone 37 of the platen, through the fabric, through the zone 37 of the bed plate, through the drilled lead 44 and into the chamber 43. It is then drained off through pipe 45. The operation of the platen is, however, timed so that as soon as the fabric is thoroughly treated, the platen is raised and no more acid is drawn through. This minimizes the amount of acid which is sucked through into the chamber 43.

The driving and timing mechanism of the machine is illustrated in Figs. 3 and 4. The motor 25 drives the main shaft 24 through a worm gear and pinion or by any other desired means. On the shaft 24 are the two cams 23 which raise and lower the platen. Also on the shaft 24 is the gear 50 which meshes with the idler gear 51. Gear 51 is on shaft 52 which is supported through a bearing and bracket by the L beam 27. The idler gear 51 meshes with gear 53 which is on shaft 54 also supported by L beam 27. On the shaft 54 is a mutilated gear 55. That is, in the gear 55 the teeth are not cut all the way around the circumference but a certain portion of the circumference is left blank. This gear meshes with gear 56 which has exactly the same number of teeth as there are in gear 55, and which also has a short curved portion 57 along which the blank portion of the gear 55 will slide when these two portions of the gears 55 and 56 come together. Gear 58 is on the same shaft as gear 57, both of said gears being keyed or otherwise attached to the shaft. Gear 58 meshes with gear 59 which is on the same shaft as the roller 5, and which when turned, will operate the said roller. The number of teeth which are left out of gear 55 and the consequent length of time during which the blank portion of gear 55 is sliding over the portion 57 of gear 56, correspond with the time during which, through the action of the cams, the platen is pressing on the fabric.

That is to say, when the platen is holding the fabric down, the rolls 5 are not operating and as soon as the jaws are separated the rolls 5 are started, and the fabric is drawn through until the platen has almost reached the fabric on its downward course. The length of fabric which is drawn through by the rolls 5 may be varied by changing the sizes of gears 58 and 59.

In Fig. 3 the platen is shown in its highest position. The cams 23 which raise the platen are in their central position, and a further rotation thereof will start the platen downward. It will be noted that the gears 55 and 56 are meshed so that just half the teeth on each of the gears are on each side of the point of contact. In other words, the gears 58 and 59 have operated the rolls 5 so that one half of the new strip of fabric has been pulled through. Now, as the cams continue to turn and the platen descends, the gears 55, 56, 58 and 59 will continue to operate and the fabric will continue to be pulled through until the platen is just clear of the fabric. At this point the blank portion of the gear 55 will engage with the blank portion 57 of the gear 56 and the said gear 56 will cease to operate. This will stop the gears 58 and 59 and the rollers 5. The fabric, therefore, will not be pulled through and the platen will then come in contact with the fabric and the acid treatment will be performed.

The gear 9 on shaft 54 is provided with a chain 8 which engages the gear on the conveyer shaft 60 shown in Fig. 1 and hereinbefore described. The said gear 9 rotates continuously, thus driving the conveyer belt at a uniform speed, the speed of the conveyer having such relation to the speed with which fabric is fed through the rolls 5 that the loops of fabric as shown in Fig. 1 will be formed thereby.

It will be noted that the point of tangency of the rolls 5 and also of the rolls 2 is slightly above the level of the bed plate. When the platen is raised and the rolls 5 begin to pull the fabric through, the said fabric will be lifted clear of the bed plate. This is to prevent the acid from smearing over the fabric, as would occur if the fabric was pulled across the surface of the bed plate. The rolls 5, as illustrated in Fig. 4, are shaped so that only the edges of the fabric are gripped between them. This type of roll is used to prevent the spreading of the acid over the untreated portions of the fabric. It may be found, however, that the degree of spreading caused by ordinary cylindrical rolls is not harmful to the fabric, in which event the rolls illustrated may be substituted for the other type.

The fabric to be treated may be either a straight fabric or a curved fabric. If the fabric is curved as described, for example,

in United States patent to Morgan No. 1,254,339, the rolls 5 and 2 may be slightly tapered so as to allow for the curve in the fabric. Also it may be advisable to provide 5 guides for the fabric as shown in Fig. 2. As illustrated, the narrow strips of metal 61 are secured to the upper surface of the bed plate. These strips will be straight and parallel if a straight fabric is being used, and 10 they will be curved if a curved fabric is being used. As the platen moves down the slots 62 in the platen will move down over the strips 61. The fabric will thus be provided with accurate guides and the correct 15 placement of the acid treatment insured.

It may be found desirable to place a coloring matter in the acid solution so as to define sharply the portion of the fabric which has been treated. This would facilitate the 20 subsequent cutting out of the collars. Such coloring matter, however, should be of a type which will be completely taken out in the laundering or bleaching process.

The terms and expressions which we have 25 employed are used as terms of description and not of limitation, and we have no intention, in the use of such terms and expressions of excluding any equivalents of the features shown and described, or portions thereof, but recognize that various 30 modifications are possible within the scope of the invention claimed.

What we claim is:

1. In a fabric treating machine the combination of two relatively movable members 35 between which the fabric is adapted to pass, means for moving one of said members relative to the other, fluid containing means mounted upon one of said members and 40 means, including pervious elements mounted upon both of said members, for causing fluid to flow through the fabric when the latter is located between said members.

2. In a fabric treating machine the combination of two relatively movable members 45 between which the fabric is adapted to pass, means for moving one of said members relative to the other, fluid containing means mounted upon one of said members and 50 means, including pervious elements mounted upon said members and vacuum producing means operatively connected to one of said elements, for causing fluid to flow through the fabric when the latter is located between 55 said members.

3. In a fabric treating machine the combination of a bed plate and a reciprocating platen between which the fabric is adapted 60 to pass, means for moving the platen toward and from the bed plate to grip and release the fabric, fluid containing means mounted upon the platen, and means for causing fluid to flow through the fabric when the latter is gripped between said bed plate and 65 platen.

4. In a fabric treating machine the combination of a bed plate and a reciprocating platen between which the fabric is adapted to pass, means for moving the platen toward and from the bed plate to grip and release 70 the fabric, fluid containing means mounted upon the platen, and means, including pervious elements mounted upon both the bed plate and the platen, for causing fluid to flow through the fabric when the latter is 75 gripped between said bed plate and platen.

5. In a fabric treating machine the combination of a bed plate and a reciprocating platen between which the fabric is adapted 80 to pass, means for moving the platen toward and from the bed plate to grip and release the fabric, fluid containing means mounted upon the platen, and means, including pervious elements mounted upon both the bed plate and the platen, and vacuum 85 producing means operatively connected to the pervious element which is mounted upon the bed plate, for causing fluid to flow through fabric which is gripped between said bed plate and platen. 90

6. In a fabric treating machine the combination of a bed plate and a reciprocating platen between which the fabric is adapted to pass, means for moving the platen toward and from the bed plate to grip and release 95 the fabric, means for drawing the desired length of fabric through while the bed plate and platen are separated, fluid containing means, including a chamber having at least part of the bottom thereof made of alundum, mounted upon the platen, and means, including a chamber having at least part of the top thereof made of alundum mounted upon the bed plate, said alundum portion being of the same size and shape as that in the platen, and vacuum producing means operatively connected to the bed plate chamber, whereby fluid is caused to flow through fabric gripped between the bed plate and platen. 100 105

7. In a fabric treating machine the combination of two relatively movable members between which fabric is adapted to pass, means for moving one of said members relative to the other, fluid containing means mounted upon one of said members, means for causing fluid to flow through the fabric when the latter is located between said members, a washing chamber, and conveying means adapted to convey the fabric from 115 said members to said washing chamber. 120

8. In a fabric treating machine the combination of a bed plate and a reciprocating platen between which fabric is adapted to pass, means for moving the platen toward and from the bed plate, fluid containing means mounted upon one of said members, means for causing fluid to flow through the fabric when the latter is gripped between 125 the bed plate and platen, a washing chamber, 130

ber, and conveying means adapted to convey the fabric from said bed plate and platen to said washing chamber.

9. In a fabric treating machine a reservoir for treating fluid, a pair of relatively movable members between which the fabric is adapted to lie, means for producing a differential in pressure, and means, including

pervious elements, mounted on said members and constructed and arranged to force ¹⁰ the fluid through the fabric when the members are in close proximity.
